8989 $\frac{1}{2}$ X

W. A. HERRICK,
CHURN.

Patented July 21, 1835.

William A. Merrick of Lanes, in the State of Maine

Letter Patent -

The subscriber referred to in these letters patent and making part of the same, containing a description on the subject of the same, William A. Merrick himself of his improvement in the common chow.

To all to whom these presents shall come

Be it known that I William A. Merrick, of Lanes in the County of Kennebec, and State of Maine, have invented a new and useful improvement in the common chow, and that the following is a full and exact description of the construction of operation of the said machine as invented as purposed by me, reference being had to the accompanying plate of figs. - Plate I. fig. 1 represents a view of my said chow in operation. It will be firmly fixed to a platform. B. is the frame made of wood, the dashers being made in the form of a cross, with one end of the cross cut off so as to afford the two to come into contact. There may be one or more dashers applied to a end. C. are two bars or iron bolts in an angle with the top of a firm upright post. These bars may be hung apart by in the middle or near to one another and so as to increase or diminish the time longer. D. D. are two upright pins into the ends of the bars which when set are attached to a double crank, E. is the crank by which the chow is operated. Plate II. fig 1. is a linear view of the same, showing what I specifically claim & for which I ask an exclusive right in the arrangement of cranks and bars for the working or operating two or more dashers for the purpose of chowing up some object. I do not deny that the above is a true representation of my said improvement as so described, I have invented the same

the sixth day of May 1855.

Witness, to this, I, William A. Merrick

I, Isaac N. Thomas
